DESIGN FOR A COMB

Lester T. Sawyer, Leominster, Mass.

Application June 18, 1947, Serial No. 139,778

Term of patent 14 years

(Cl. D86—8)

To all whom it may concern:

Be it known that Lester T. Sawyer, a citizen of the United States, residing at Leominster, in the county of Worcester and State of Massachusetts, has invented a new, original, and ornamental Design for a Comb, of which the following is a specification, reference being had to the accompanying drawing forming part thereof.

Fig. 1 is a view in front elevation of a comb showing my new design;

Fig. 2 is an edge view; and

Fig. 3 is a side elevation.

The essential features of my design reside in the portions shown in full lines.

I claim:

The ornamental design for a comb, as shown and described.

LESTER T. SAWYER.
